ATTORNEY

UNITED STATES PATENT OFFICE.

HERMAN W. BRANDT, OF ANTIGO, WISCONSIN.

GARAGE-DOOR OPENER AND CLOSER.

Application filed December 6, 1922. Serial No. 605,202.

To all whom it may concern:

Be it known that HERMAN W. BRANDT, who says he is a citizen of the United States of America, residing at Antigo, in the 5 county of Langlade and State of Wisconsin, has invented certain new and useful Improvements in Garage-Door Openers and Closers, of which the following is a specification.

10 This invention relates to garage or other building doors and particularly to a mechanism whereby they may be conveniently opened and closed, as for instance by a motor vehicle or wagon driver without leaving his seat or vehicle.

15 The particular object of my invention is to provide a mechanism whereby the two folding or swinging doors of a building may be simultaneously opened or closed by 20 the manipulation of a single operating cable.

25 Other features reside in the particular structural elements which include a simple operating gearing, an automatic latching mechanism for the doors at each end of their movements, the arrangement of the controlling cables and other novel details of construction.

30 In the accompanying drawings:— Figure 1 is an inside view of a portion of a building showing the doors in closed position.

35 Figure 2 is a vertical sectional view taken on the line 2—2 of Figure 1, looking in the direction of the arrows, and.

40 Figure 3 is a horizontal section through one of the doors and its supporting frame on the line 3—3 of Figure 2, the door being shown in open position in dotted lines.

45 Referring now more specifically to the accompanying drawings by numerals of reference, 2 indicates a building such as a garage, stable or the like, the door frame for which is shown at 3, 4, representing the vertical members and 6 the top horizontal member thereof.

50 Hung on hinges 8 on the vertical members of the door frame are the double doors 10 and 12.

55 In view of the fact that the operation and construction of each of the doors is similar to the other, a description of one will be sufficient, it being of course understood that the mechanism on one door operates in a reverse manner to the other.

Referring particularly to Figure 3, which

illustrates in full lines, the door in closed position, and in dotted lines, in open position, 14 indicates a plate attached to the inner face of each of the vertical door frame members 4, said plate being firmly secured in place and provided with a horizontal bracket 16. The upper portion of the plate 14, above the bracket 16 is provided with a transverse opening adapted to receive a bearing bolt or pin 18 upon which is journaled a bevel gear 20 having an integral or rigid radial lever arm 22.

The gear 20 is in mesh with a horizontal oscillatory bevel gear 24 journaled on a vertical bearing bolt or pin 26 on the plate bracket 16, said gear 24 also being provided with a horizontal radial rigid or fixed arm 28, the outer end of which is curved outwardly as at 30 and carries an antifriction roller 32 journaled on a vertical pivot or axis 34.

During the opening and closing operation, of the door, the roller 32 cooperates with a horizontally slotted guide iron or strap 36 secured to the door by suitable fastening devices 38, the body of the guide iron or strap being spaced away from the inner face of the door to provide a runway for the roller which is designed to straddle the slot 35 in the strap 36. For the sake of convenience in manufacture, the radial arm may be formed separate from the body of its carrying portion and to which it may be secured by adjustable bolts 40.

The doors are opened and closed through the medium of pull cords, or cables 42, and 44, which pass through a tubular horizontal arm 46, supported upon the door frame upon its outer side by a bracket arm 48, the tubular metal arm extending a sufficient distance from the front of the building to permit the operator of a vehicle, opening the doors without leaving his seat.

The operating cables or ropes extend inwardly through the tubular arm 46 and within the building, passing thence over guide pulleys 50 and 52 upon opposite sides of the door frame respectively at the top thereof and over guide pulleys 54 below the point of attachment of the plates 14 to the side members of said frame. For the sake of definiteness, the opening cable will be referred to as 42 and the closing cable as 44.

The cables 42 and 44 which of course co-operate respectively with the operating

mechanism upon each door, are interconnected so that they operate in unison from a single pull rope upon the outside of the building as shown in Figure 2.

- 5 Each of the opening and closing cables is connected with its operating lever 22 by being passed around a pulley 55 journalled on the lever adjacent its outer end at 56, so that it has frictional engagement there-

10 with.

The cables 42 and 44, respectively after passing around the pulley 54 are connected with parallel latch bolts 60 and 62 which slide in transverse guides 64 and on the 15 lever 22, and cooperate with a pair of notches 66 at opposite ends of a sector 68. The latches are normally urged toward latching position through compression springs 70 coiled around the latch bolts and 20 confined between a stop thereon and the outer one of the transverse guides 64.

Briefly, the operation of the door opening and closing mechanism is as follows:—

Assuming the doors are closed, as in full 25 lines in Figure 3, the operator, by pulling on the cord 42, outside the building, through its continuation on the inside, primarily retracts the latch bolt 60 from the lower notch 66 in the sector 68, after which, a continued 30 pull on the rope, will elevate the lever arm 22 and through the bevel gearing, swing the arm 28 and open the doors. At the end of the opening operation, the opposite latch bolt snaps into the upper notch 66 and 35 thereby holds the door open. A reversal of the operation is performed by a pull on the closing rope 44.

From the foregoing description of the construction of my improved apparatus, it 40 will be seen that I have provided a simple, inexpensive, and efficient means for carrying out the objects of my invention and while I have described the elements best adapted to perform the functions set forth, 45 it is obvious that various changes in form, proportion and in the minor details of construction may be resorted to without departing from the spirit or sacrificing any of the principles of the invention.

50 What I claim as new is:—

1. In a door opening and closing mechanism, in combination with the vertical door frame members and the doors hinged thereon, a plate mounted on each of said 55 frame members, a bevel gear journalled on said plate in a vertical plane, a radial operating lever rigid with said gear, a second bevel gear journalled on said plate perpendicular to said first gear and in mesh

therewith, an arm rigid with said second gear, a guide strap secured to the face of the door, a sliding connection between the outer end of the arm and said guide strap and pull cables connected with each of said operating levers for controlling the opening and closing of said doors.

2. In a door opening and closing mechanism, the combination with a vertical door frame and a door hinged thereto; of a base plate mounted on said frame member, said plate having an arcuate portion formed thereon provided at predetermined points in its peripheral edge with notches, a bevel gear journalled on said plate on a horizontal axis, a radial operating lever carried by said gear, a second bevel gear supported for rotation on said plate on a vertical axis and meshing with the first mentioned gear, a radial arm rigidly carried on the second gear and having its outer end in sliding engagement with said door, latch members carried by said lever adapted for engagement with the notches of said plate to hold said lever and correspondingly lock said door in its adjusted positions, and pull cables having connection with said lever and also actuating said latch members.

3. In a door opening and closing mechanism, the combination with a vertical door frame and a door hinged thereto; of a base plate mounted on said frame member, said plate having an arcuate portion formed thereon provided at predetermined points in its peripheral edge with notches, a bevel gear journalled on said plate on a horizontal axis, a radial operating lever carried by said gear, a second bevel gear supported for rotation on said plate on a vertical axis, and meshing with the first mentioned gear, a radial arm rigidly carried on the second gear and having its outer end in sliding engagement with said door, a pulley mounted on the free end of said lever, a pair of parallel spring-forced latch members extending longitudinally of said lever and adapted for engagement with the notches in the arcuate portion of the aforesaid plate to lock said lever and correspondingly said door in adjusted positions, and a pair of pull cables extending through said frame members and from opposite directions extended over said pulley and connected respectively with said latch members, as and for the purposes described.

In testimony whereof I affix my signature.

HERMAN W. BRANDT
